UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

FOLDER.

Application filed June 25, 1926, Serial No. 118,451, and in Canada May 26, 1924.

This is a continuation in part of my application for patent, Serial No. 580,437, filed August 8, 1922 and a continuation in part of my divisional application Serial No. 5,310, filed January 19, 1925.

The principal objects of this invention are to provide for operating a folder at a high rate of speed and to provide improvements in the nipping roll arrangement to 10 divide and reduce the strain on the paper so as to prevent the failure of these rolls to pull the paper snugly over the former when running at high speed and avoid the tearing of the margins.

15 Reference is to be had to the accompanying drawings, in which—

Fig. 1 is a side view of a newspaper folding machine constructed according to this invention, partly diagrammatic to show the 20 path of the paper;

Fig. 2 is a diagrammatic view showing the drive for the nipping rolls; and

Fig. 3 is a side view showing the spring pressed brackets for the nipping rolls.

25 I find that when newspaper folding devices are run at great speed an ordinary set of nipping rolls running on the margins does not pull the paper snugly over the former. If they are set tight enough on the 30 paper to accomplish this object they bring too great a strain on one of the newspaper streams and it cracks or breaks through at that point. To overcome this difficulty I provide for dividing up this strain between 35 two or more sets of nipping rolls running at a surface speed faster than that of the web.

I have shown the invention as applied 40 to a folding mechanism having the ordinary features well known in this art and the improvements above mentioned added to them. This machine is shown as comprising a former 10 operating with the usual forming or leading-in rolls 11, and the usual 45 pair of nipping rolls 12 engaging the margins which I call the primary nipping rolls. On account of the difficulties above mentioned and for the purpose of dividing up the strain I do not depend upon these two 50 pairs of nipping rolls. But I provide in addition a secondary set of nipping rolls 13 spaced from the first set and operating in the same way on the margins.

The rolls of both sets are driven from the 55 folder by a shaft 21 and bevel gears 22 so as

to run at a surface speed higher than that of the paper. They are geared to run both sets by a train of gearing 23. These rolls are driven at a higher speed for the specific purpose of pulling up the sheet and making 60 it taut. Without this speeding up or acceleration, this work of pulling up would be imposed on the folding and cutting cylinder with resulting pin tears, etc. It is most desirable that the folding and cutting 65 cylinder have only their normal functions to perform, that is, literally, cutting and folding. Both sets of nipping rolls run at exactly the same speed.

With this device it is not necessary to 70 adjust the rolls 12 tight enough to cause them to pull the paper snugly over the former 10 at all times, but they can be adjusted more loosely because they are assisted by the second rolls 13 which also are 75 adjusted loosely. The work is divided between the plurality of sets and the strain at each point is divided and lessened. This practically eliminates the cracking or breaking 80 of the paper at the margins by the nipping rolls.

I have shown one pair of the upper set 85 of nipping rolls 12 mounted in fixed position and the other on a shaft mounted on pivoted brackets 14. These brackets are pressed by adjustable springs 15 toward the other member of the couple and this adjustment may be made by a worm and screw 16 or in any other desired way. One pair 90 of the rolls 13 of the other set is also mounted in fixed position on the frame of the machine and the other on a bracket 17 which is pivoted and adjusted by springs 15 and screws 16 as in the other case.

The web W is led as usual from the nipping rolls to the folding cylinder 18 and cutting and collecting cylinder 19 which cut it up into sheets and fold it in the usual way and tuck it between the folding rolls 20.

These improvements are designed to facilitate the speeding up of a folding device of the character indicated in the drawings, and to solve certain problems which arise when the speed of the folder increases materially beyond the highest rates heretofore 100 considered practical and they cooperate to that end.

Although I have illustrated and described only a single form of the invention and 110 shown it as applied to one type of folder I

am aware of the fact that modifications can be made therein by any person skilled in the art without departing from the scope of the invention as expressed in the claims.

5. Therefore, I do not wish to be limited in these respects, but what I do claim is:—

1. In a folding machine, the combination with a former and leading-in rolls, of means for nipping the web and pulling it through 10 the rolls from a plurality of points along the web for the purpose of dividing the strain, said means at each of said points comprising two rolls rotatably mounted one roll being yieldingly held in contact with 15 the other.
2. In a folding machine, the combination with forming and leading-in rolls, of means for nipping the web and pulling it through the rolls from a plurality of points along 20 the web for the purpose of dividing the strain, said means at each of said points comprising a roll rotatably mounted on a stationary shaft and another roll yieldingly held in contact therewith and mounted on 25 a shaft carried by a pivoted bracket.
3. In a folding machine, the combination with the forming or leading-in rolls, and a pair of nipping rolls for engaging the folded web, one of said rolls being yieldingly and 30 rotatably mounted in contact with the other and drawing the web through the forming rolls, of a secondary means for engaging said web at another point and assisting in drawing it through the folding rolls.
- 35 4. In a folding machine, the combination with the former and a rotary folding device, of two pairs of rolls located between them for constantly engaging the web at a plurality of points along its length and pulling 40 it through the former and advancing it to the folder, one roll of each pair being yieldingly mounted.
- 45 5. In a folding machine, the combination with the forming or leading-in rolls and a pair of nipping rolls for engaging the folded web, one of said rolls being rotatably mounted on a shaft and the other yieldingly and ro-

tatably mounted in contact therewith and drawing the web through the forming rolls, of a secondary means for engaging said web 50 at another point and assisting in drawing it through the folding rolls, said secondary means comprising a pair of rolls, one being yieldingly mounted on a pivoted bracket.

6. In a folding machine, the combination with a former and leading-in rolls, of means for nipping the web and pulling it through the rolls from a plurality of points along the web for the purpose of dividing the strain and means for running the nipping 60 means at a surface speed greater than web speed for the purpose of dividing the strain.

7. In a folding machine, the combination with the former and a rotary folder for receiving the web therefrom, of a primary pair of nipping rolls between the former and folder for nipping and feeding the web, a secondary pair of nipping rolls also located between the former and folder at a distance 70 from the primary nipping rolls for engaging the web and assisting in pulling it through the former and advancing it to the folder and means for rotating the nipping rolls at a surface speed greater than 75 that of the web.

8. In a folding machine, the combination with the former and a rotary folder for receiving the web therefrom, of a primary set of nipping rolls between the former and 80 folder for nipping and feeding the web at its margins, a secondary set of nipping rolls also located between the former and folder at a distance from the primary nipping rolls for engaging the web at its margins and as- 85 sisting in pulling it through the former and advancing it to the folder, both sets of rollers being adjustable to nip the paper at the margins with less pressure than would be necessary with a single set.

In testimony whereof I have hereunto affixed my signature.

HENRY A. WISE WOOD.

- am aware of the fact that modifications can be made therein by any person skilled in the art without departing from the scope of the invention as expressed in the claims.
- 5 Therefore, I do not wish to be limited in these respects, but what I do claim is:—
1. In a folding machine, the combination with a former and leading-in rolls, of means for nipping the web and pulling it through 10 the rolls from a plurality of points along the web for the purpose of dividing the strain, said means at each of said points comprising two rolls rotatably mounted one roll being yieldingly held in contact with 15 the other.
  2. In a folding machine, the combination with forming and leading-in rolls, of means for nipping the web and pulling it through the rolls from a plurality of points along 20 the web for the purpose of dividing the strain, said means at each of said points comprising a roll rotatably mounted on a stationary shaft and another roll yieldingly held in contact therewith and mounted on 25 a shaft carried by a pivoted bracket.
  3. In a folding machine, the combination with the forming or leading-in rolls, and a pair of nipping rolls for engaging the folded web, one of said rolls being yieldingly and 30 rotatably mounted in contact with the other and drawing the web through the forming rolls, of a secondary means for engaging said web at another point and assisting in drawing it through the folding rolls.
  - 35 4. In a folding machine, the combination with the former and a rotary folding device, of two pairs of rolls located between them for constantly engaging the web at a plurality of points along its length and pulling 40 it through the former and advancing it to the folder, one roll of each pair being yieldingly mounted.
  5. In a folding machine, the combination with the forming or leading-in rolls and a 45 pair of nipping rolls for engaging the folded web, one of said rolls being rotatably mounted on a shaft and the other yieldingly and ro-
- tatably mounted in contact therewith and drawing the web through the forming rolls, of a secondary means for engaging said web 50 at another point and assisting in drawing it through the folding rolls, said secondary means comprising a pair of rolls, one being yieldingly mounted on a pivoted bracket.
6. In a folding machine, the combination with a former and leading-in rolls, of means for nipping the web and pulling it through the rolls from a plurality of points along the web for the purpose of dividing the strain and means for running the nipping means at a surface speed greater than 55 web speed for the purpose of dividing the strain.
7. In a folding machine, the combination with the former and a rotary folder for receiving the web therefrom, of a primary pair of nipping rolls between the former and folder for nipping and feeding the web, a secondary pair of nipping rolls also located between the former and folder at a distance 60 from the primary nipping rolls for engaging the web and assisting in pulling it through the former and advancing it to the folder and means for rotating the nipping rolls at a surface speed greater than 65 that of the web.
8. In a folding machine, the combination with the former and a rotary folder for receiving the web therefrom, of a primary set of nipping rolls between the former and 70 folder for nipping and feeding the web at its margins, a secondary set of nipping rolls also located between the former and folder at a distance from the primary nipping rolls for engaging the web at its margins and assisting in pulling it through the former 75 and advancing it to the folder, both sets of rollers being adjustable to nip the paper at the margins with less pressure than would be necessary with a single set.
- 90 In testimony whereof I have hereunto affixed my signature.

HENRY A. WISE WOOD.

CERTIFICATE OF CORRECTION.

Patent No. 1,640,017.

Granted August 23, 1927, to

HENRY A. WISE WOOD.

It is hereby certified that error appears in the printed specification of the above numbered patent requiring correction as follows: Page 2, lines 62 and 63, claim 6, strike out the words "for the purpose of dividing the strain"; and that the said Letters Patent should be read with this correction therein that the same may conform to the record of the case in the Patent Office.

Signed and sealed this 18th day of October, A. D. 1927.

M. J. Moore,

Acting Commissioner of Patents.
